D11-108. OR D19,319 EX

DESIGN.

—o—

T. H. BACHELER.
BADGE.

No. 19,319.

Patented Sept. 24, 1889.

UNITED STATES PATENT OFFICE.

THOMAS H. BACHELER, OF CHICAGO, ILLINOIS.

DESIGN FOR A BADGE.

SPECIFICATION forming part of Design No. 19,819, dated September 24, 1889.

Application filed June 26, 1889. Serial No. 815,640 1/4. Term of patent 3 1/2 years.

To all whom it may concern:

Be it known that I, THOMAS H. BACHELER, a citizen of the United States, residing at Chicago, in the county of Cook and State of Illinois, have invented and produced a new and original Design for a Badge, of which the following is a specification, reference being had to the accompanying drawing, forming part thereof.

10 The badge comprises a thin disk of any suitable material having upon one of its surfaces the ornamental design illustrated in the cut.

The several parts of the design are referred 15 to by letters as follows:

a is a circular raised ring forming the peripheral boundary of the ornamental surface.

b is a rhombic-shaped figure in outline located centrally across the face of the badge.

c c are two lines parallel to each other and 20 to two of the parallel sides of the figure *b*, and located to divide the figure *b* into three nearly equal spaces or bars *d e f*.

Twelve stars *g g* are arranged in a circle and spaced symmetrically near to the ring *a*, 25 as shown. The ring *a* and the stars *g g* are raised above the body of the badge and their surfaces are always in a common plane.

I claim as my design and invention—

The design for a badge herein shown and 30 described, the same comprising the ring *a*, the rhombic figure *b*, with lines *c c*, and the bars *d e f*, as set forth.

THOMAS H. BACHELER.
